UNITED STATES PATENT OFFICE.

STUART W. CRAMER, OF CHARLOTTE, NORTH CAROLINA.

AIR-CONDITIONING APPARATUS.

1,073,475.

Specification of Letters Patent. Patented Sept. 16, 1913.

Original application filed April 15, 1909, Serial No. 490,079. Divided and this application filed January 11, 1910. Serial No. 537,568.

To all whom it may concern:

Be it known that I, STUART W. CRAMER, a citizen of the United States, residing at Charlotte, in the county of Mecklenburg and State of North Carolina, have invented 5 certain new and useful Improvements in Air-Conditioning Apparatus; and I do hereby declare the following to be a full, clear, and exact description of the invention 10, such as will enable others skilled in the art to which it appertains to make and use the same.

This invention relates to apparatus for 15 treating air, whereby the air is cleansed of its impurities, and is conditioned by the addition or subtraction of moisture and heat as may be desired.

The object of this invention is to provide 20 an apparatus whereby air cleansing, moistening, heating and cooling are attained as heretofore in similar types of apparatus, with the further advantage that cooling 25 may also be continued even though moistening be discontinued, and without the aid of refrigeration, the circulation of cold water, or other liquids, or the like.

The invention consists in certain improvements which will be fully disclosed in the 30 following specification and claims.

This application is a division of my application for a patent filed April 15th, 1909, Serial Number 490,079.

In the accompanying drawings, which 35 form part of this specification:—Figure 1 represents an isometric view of an apparatus using a single cold air tube, being an adaptation of my invention to the individual head type of air conditioning apparatus. Fig. 2 represents a plan view of the 40 same. Fig. 3 represents a side elevation of the same, and Fig. 4 represents a side elevation of a modification of the same type of apparatus.

Reference being had to the drawings and 45 the designating characters thereon, the numeral 1 indicates an inner tube which forms the spray or moistening chamber, 2 an annular air cooling chamber between the tube 1 and the outer tube 3. 4 the spray-heads, 50 5 and 6 the fans. 7 and 8 the ducts for supplying air from outside the building and 10, 11 the dampers.

The operation of this device is readily discernible without further elucidation. In the tube 1, one or more spray heads 4 may be 55 used, a fan 5 may be used to move the air in said tube, or it may be moved by the inductive effect of the sprays alone. It will be noticed that in all of the types embodied in this invention, it is possible to control the 60 humidity in a room by opening and closing the damper 12, which either admits the moistened air to the room or directs it out through the roof or side wall of the building as may be desired. 65

In Fig. 4 air may be supplied from inside the building by a fan 13 to supply the air cooling chamber 2, and air drawn through pipe 14 from outside the building to supply the spray or air moistening chamber. 70 15 indicates the pipe through which moistened air may be conducted outside the building, under control of damper 12.

Further elucidation is deemed unnecessary, as the foregoing description with the 75 accompanying drawings will suggest to anyone skilled in the art to which my invention appertains some of the various modifications of which the invention is susceptible. 80

It is obvious that in lieu of the spray heads shown, other devices may be employed for cooling by the evaporation of the moisture, and that changes in form and arrangement may be made without departing from 85 the spirit of my invention.

Having thus fully described my invention, what I claim is—

1. In an air conditioning apparatus, an air chamber, a fan for producing a current 90 of air through the air chamber, a spray chamber within said air chamber, spray heads for moistening, cooling and inducing a secondary current of air through said spray chamber, and means for controlling 95 the supply of air from said fans.

2. In an air conditioning apparatus, a spray chamber, spray heads within said spray chamber, and arranged for inducing a current of air through said spray chamber, an air cooling chamber surrounding said spray chamber, a fan for producing a current of air through the cooling chamber but closed from the spray chamber, and 100

means for controlling the supply of air from said fan.

3. In an air conditioning apparatus, a spray chamber, spray heads within said spray chamber, a concentrically arranged air cooling chamber, a fan connected to the spray chamber, a fan connected to the air cooling chamber, and a damper to differ-

entially control the supply of air from each chamber.

In testimony whereof I affix my signature, in presence of two witnesses.

STUART W. CRAMER.

Witnesses:
